UNITED STATES PATENT OFFICE.

HENRY P. HEEREN, OF LAKE TOWNSHIP, WOOD COUNTY, OHIO.

INTERNAL-COMBUSTION ENGINE.

Application filed January 9, 1925. Serial No. 1,342.

To all whom it may concern:

Be it known that I, HENRY P. HEEREN, a citizen of the United States, and a resident of Lake Township, in the county of Wood 5 and the State of Ohio, have invented a new and useful Internal-Combustion Engine, which invention is fully set forth in the following specification.

My invention has for its object to provide a valve mechanism for internal combustion engines whereby large port openings, that is, port openings having large cross sectional areas may be quickly opened and closed at the proper times in the cycle of 10 operations of the engine, and which are operated by the ordinary cam shaft of the engine. The valves are so constructed that the passage ways to and from the engine forming the intake, and exhaust passage 15 ways are operated to their full extent by a very short movement of the valves and yet produce openings of a large cross sectional area for the admission of vapors on the one hand and the exit of exhaust gases on 20 the other. The invention also provides features and advantages that will appear in the following description and upon examination of the drawings.

The invention may be contained in internal combustion engines of different forms. To illustrate a practical application of the invention and to present a description thereof in detail, I have selected an engine containing the invention as an example of the 30 different embodiments of my invention, and shall describe it hereinafter. The engine selected as an example is shown in the accompanying drawings.

Figure 1 of the drawings illustrates a top view of the engine, a part being shown broken away. This part shows the valve members in section. Fig. 2 illustrates a side and broken view of the engine. Fig. 3 illustrates a view of a section taken on the line 45 3—3 indicated in Fig. 2.

The engine 1 has a head 2 that may be located on the cylinder block 3 of any of the well known types of internal combustion engines. The cylinder block 3 is provided 50 with the cylinders 4, in which are located the pistons 5. The head 2 is provided with spark plugs 6 that ignite the fuel that is drawn into the cylinders and compressed by the pistons in the manner well known in the 55 art. The head 2 is provided with a water chamber 7 that communicates with the

chamber 8 located in the cylinder block 3. The chambers 7 and 8 form the usual water jacket for maintaining the engine as cool as may be. 60

The valves for controlling the intake and outflow of the gases are located in the head 2. The valves 9 and 10 are cylindrical in form and are located in shells 11 that are formed integral with the head 2 at points above the cylinders 4. They control the flow of the gases through the ports 12 and 13. The interior of the valves 9 communicate with the exhaust manifold 14 for carrying away the products of combustion while the valves 10 65 are connected to the intake manifold 15 and control the flow of the fuel mixture into the ignition chambers 16 located in the head 2 of the engine. The ports 12 and 13 are in the form of long slots having, comparatively 70 speaking, a narrow width and the valves 9 and 10 are provided with the ports 18 having a length and width substantially the same as the length and width of the ports 12 and 13, and so that when the ports 18 75 register with the ports 12 and 13 the passage way from the manifolds to the combustion chambers of the engine will be opened, and so that by slight rotation of the valves 9 and 10 the passage ways will be closed. The 80 ports 13 are located directly above the spark plugs 6 that extend horizontally through the side wall of the engine head which operates to clean the spark plugs by the flow of the gas and assures an atmosphere of a 85 combustible mixture about each spark plug and insures an explosion or firing of the cylinders in their proper sequence. 90

The valves 9 and 10 are closed at one end and are so formed as to abut the wall of the 95 head. The exhaust valves 9 are pressed against the side wall of the head with considerable pressure, owing to the pressure produced at the time that the valve is opened during the escape of the burnt gases. The 100 wall of the head is provided with anvils 19 that are located centrally with respect to the axis of rotation of the valves 9 and 10. The anvils 19 are bosses that are formed integral with the side wall of the head. The openings 105 of the manifolds register with the openings of the cylindrical chambers 9 and 10 and preferably have diameters at these points larger than the interior diameters of the cylindrical valves. 110

The side wall 20 of the head is made removable and is secured to the body of the

head by means of the bolts 21. The wall 20 forms a cover for covering one side of the head. It forms a chamber in which the part of the mechanism for operating the valves is located. The anvils 19 are located on the cover 20 and the valves are provided with projections 22 that make contact with the anvils 19. The projections have recesses 23 that communicate with channels 24 that extend along the upper sides of the valves. The recesses 23 are located below a pipe 25 having openings that are located above the recesses 23. The pipe 25 connects with an oil pump and the oil is fed from the well of the crank shaft casing into the pipe 25, in the manner well known in the art and then drips through the openings 26 into the recesses 23. It flows along the channels 24 and thus lubricates the entire surface of the valves 9 and 10.

The valves 9 and 10 are operated by means of the push rods 27 that are actuated by the cams 28 of the cam shaft 29. The projections 22 are provided with recesses 30 in which the upper ends of the rods 27 are maintained by means of the springs 31 that operate to tilt the projecting parts 22 of the valves against the ends of the rods 27, the rods being located on the opposite sides of the axes of the valves from that on which the springs are located. As the valves are tilted back and forth the oil that drips from the pipe 25 works back in between the surfaces of the valves and their shells 11. The springs 31 are secured in position by means of the knobs 32 that are located on the projecting parts 22 of the valves, and the knobs 33 that are located on plates 34. The plates 34 rest upon the cylinder block 3 of the engine and are maintained in their positions by the rods 27 that extend through the plates 34.

Thus by my invention I have provided an exceedingly simple construction whereby the parts may be readily assembled to form the engine head or the engine head may be readily taken apart for purposes of examination and of repair.

I claim:

50 1. In an internal combustion engine having a plurality of cylinders and pistons located in the cylinders, an engine head having ignition chambers, a pair of cylindrical valves located above each ignition chamber, the valves and the ignition chambers having ports for controlling the movement of the gases through the cylindrical valves to and from the cylinders, a cover plate, the cover plate having anvils contacting with the ends 55 of the cylindrical valves at the axes of the valves and means for securing the cover plate in position to secure the valves in position.

60 2. In an internal combustion engine having a plurality of cylinders and pistons lo-

cated in the said cylinders, cylindrical valves located above the said cylinders and having ports for controlling the flow of the gases to and from the said cylinders, the engine having a cam shaft, cam rods extending from the cams of the cam shaft to the cylindrical valves for tilting the said valves to open and close the connections between the cylinders and the interiors of the cylindrical valves, and springs for pressing the valves against the ends of the rods. 70

3. In an internal combustion engine having a plurality of cylinders and pistons located in the said cylinders, cylindrical valves located above the said cylinders and having ports for controlling the flow of the gases to and from the said cylinders, the engine having a cam shaft, cam rods extending from the cams of the cam shaft to the cylindrical valves for tilting the said valves to open and close the connections between the cylinders and the interiors of the cylindrical valves, and springs for pressing the valves against the ends of the rods, a cover plate for covering the ends of the valves, the ends of the rods, and the springs, and securing the valves in position. 80

4. In an internal combustion engine having a plurality of cylinders and pistons located in the cylinders, an engine head having ignition chambers, a pair of cylindrical valves located above each ignition chamber, the valves and the ignition chambers having ports for controlling the movement of the gases through the cylindrical valves to and from the cylinders, the valves having projecting parts extending from one end of each of the valves, the said parts having recesses, an oil pipe located above the said parts and having openings for permitting the oil to pass from the said pipe into the said recesses, the valves having channels communicating with the said recesses for conducting the oil over the surfaces of the valves. 90

5. In an internal combustion engine having a plurality of cylinders and pistons located in the said cylinders, cylindrical valves located above the said cylinders and having ports for controlling the flow of the gases to and from the said cylinders, the engine having a cam shaft, cam rods extending from the cam shaft to the cylindrical valves for tilting the said valves to open and close the connections between the cylinders and the interiors of the cylindrical valves, the valves having projecting parts, the parts having recesses, an oil pipe extending over the said parts and having openings for permitting oil to pass from the said pipe into the said recesses. 100

6. In an internal combustion engine having a plurality of cylinders and pistons located in the said cylinders, cylindrical valves located above the said cylinders and having

ports for controlling the flow of the gases to and from the said cylinders, the said valves having projecting parts extending from the ends of the valves, the engine having a cam shaft, cam rods extending from the cam shaft to the projections for tilting the said valves to open and close the connections between the cylinders and the interiors of the valves, the projections having recesses, an oil pipe extending over the said projections and having openings for directing the oil to the said recesses.

7. In an internal combustion engine having a plurality of cylinders and pistons located in the said cylinders, cylindrical valves located above the said cylinders and having ports for controlling the flow of the gases to and from the said cylinders, the said valves having projecting parts extending from the ends of the valves, the engine having a cam shaft, cam rods extending from the cam shaft to the projections for tilting the said valves to open and close the connections between the cylinders and the interiors of the valves, the engine having a cylinder head and a cylinder block, the valves located in the cylinder head, springs located intermediate the projections and the

cylinder block for tilting the projections against the ends of the cam rods.

8. In an internal combustion engine having a plurality of cylinders and pistons located in the said cylinders, cylindrical valves located above the said cylinders and having ports for controlling the flow of the gases to and from the said cylinders, the said valves having projecting parts extending from the ends of the valves, the engine having a cam shaft, cam rods extending from the cam shaft to the projections for tilting the said valves to open and close the connections between the cylinders and the interiors of the valves, the engine having a cylinder head and a cylinder block, the valves located in the cylinder head, springs located intermediate the projections and the cylinder block for tilting the projections against the ends of the cam rods, the projections having knobs, plates having knobs and located on the cylinder block and secured in position by the cam rods, the springs being secured in position by the said knobs.

In testimony whereof I have hereunto signed my name to this specification.

HENRY P. HEEREN.
